DESIGN FOR A TABLE LIGHTER HOLDER

Angelo Arrighi, Union City, N. J., assignor to American Safety Razor Corporation, Brooklyn,
N. Y., a corporation of Virginia

Application April 23, 1949, Serial No. 2,212

Term of patent 14 years

(Cl. D48—27)

To all whom it may concern:

Be it known that I, Angelo Arrighi, a citizen of the United States and a resident of Union City, county of Hudson, and State of New Jersey, have invented a new, original, and ornamental Design for a Table Lighter Holder, of which the following is a specification, reference being had to the accompanying drawings, forming part thereof.

Fig. 1 is a perspective view of a table lighter holder, showing my new design;

Fig. 2 is a side elevational view thereof;

Fig. 3 is a top plan view;

Fig. 4 is a bottom plan view;

Fig. 5 is an elevational view taken from one end; and

Fig. 6 is an elevational view taken from the other end.

The dotted lines shown in the drawing indicating a lighter are for illustrative purposes only.

I claim:

The ornamental design for a table lighter holder, as shown and described.

ANGELO ARRIGHI.
